ATTYS

UNITED STATES PATENT OFFICE.

OTTERBEIN KIRACOFE, OF EAST RUTHERFORD, NEW JERSEY, ASSIGNOR, BY MESNE ASSIGNMENTS, TO THE FLINTEKOTE COMPANY, OF BOSTON, MASSACHUSETTS, A CORPORATION OF MASSACHUSETTS.

ROOFING MATERIAL AND METHOD OF JOINING THE ENDS OF FELT IN MAKING THE SAME.

1,383,726.

Specification of Letters Patent. Patented July 5, 1921.

Application filed April 24, 1916. Serial No. 93,074.

To all whom it may concern:

Be it known that I, OTTERBEIN KIRACOFE, a citizen of the United States, residing at East Rutherford, in the county of Bergen 5 and State of New Jersey, have invented new and useful Improvements in Roofing Materials and Methods of Joining the Ends of Felt in Making the Same, of which the following is a specification.

10 In the manufacture of prepared roofing, long sheets of fibrous absorbent material, such as felt, paper, sheets of asbestos and the like, are caused to pass progressively through a waterproofing saturating compound held in a suitable tank, then through 15 squeeze rolls, frequently through rolls which apply a skin coating of hard pitch or asphalt, and then frequently between or under appliances which apply a coating of crushed mineral thereto. It is highly desirable that 20 the sheet should be endless so as not to interrupt the operation, particularly as it is exceedingly inconvenient to pass the loose front end of the sheet through the various 25 instrumentalities or apparatus referred to. Heretofore it has been customary to overlap and stitch the rear end of one sheet, when it is nearly exhausted, to the front end of the next sheet. This is a relatively expensive 30 operation, and causes much waste and loss of time.

My invention comprises a more effective method and means for joining the two ends of the sheet, and consists in bringing the 35 end of the exhausted roll into proximity to the end of the new roll, and then securing the ends of the sheets by means of an adhesive-coated strip of suitable material such as paper, cloth or the like.

40 On the accompanying drawing,—

Figure 1 shows my improved means for connecting two felt sheets.

Fig. 2 represents a longitudinal section through the same.

45 The two sheets are indicated at 5, 6, and they are of such material as is usually employed in the manufacture of prepared roofing sheets, strips or shingles. The ends of the sheets are placed in abutting relation,—

they need not necessarily be contiguous,— 50 though they may be in the same plane and relatively close together. A strip 7, preferably of Kraft paper (though linen, tape or other like material under some circumstances may be used), coated with a suitable adhesive, such as glue or gum, is placed on the adjacent surfaces of the sheets and pressed thereon so as to adhere thereto. The ends of the strip are folded over the side edges 55 of the sheet and are caused to adhere on the under surfaces of said sheets.

The connecting strip may be from three to six inches wide, and may be drawn from a strip-severing machine. Hence commercial gummed paper may be employed for the 60 purpose described and rendered adhesive by dampening the gum before application. I find that this simple means is effective to join the ends of the sheets, and to hold them 65 together when they are passing through the various forms of apparatus to which I have herein referred. The connecting ends may be passed between pressing rolls to insure 70 the adhesion of the connecting strip thereto. The end of each sheet is covered and held in 75 place by the connecting strip or strips. Usually it is desirable to loop the fabric prior to its immersion in the saturating tank to provide sufficient slack to permit the connection 80 between the sheets to be made without stopping the operation.

Having thus explained the nature of my 85 said invention and described a way of making and using the same, although without attempting to set forth all of the forms in which it may be made or all of the modes of its use, what I claim is:

1. The herein described method of joining or connecting separate elongated sheets of felt or the like, in the manufacture of roofing material, which consists in bringing the transverse ends of the sheets of felt together with their side edges in alinement and their ends in abutting relation, and then pasting 90 to and across said ends a transverse adhesive flexible connecting strip of paper.

2. A continuous roofing sheet, comprising 95 two elongated sheets of felt having their end

portions adjacent and their side edges in alinement, and a flexible adhesive paper strip transversely overlapping said ends and adhering thereto.

5 3. A continuous roofing sheet, comprising two elongated sheets of felt having their end portions in abutting relation and their

side edges in alinement, and a flexible adhesive binder strip or strips transversely overlapping said ends, bent around the side edges 10 thereof, and adhering to both faces thereof.

In testimony whereof I have affixed my signature.

OTTERBEIN KIRACOFE.
